United States Patent Office

Des. 186,750
Patented Nov. 24, 1959

186,750

VIBRATORY MASSAGE UNIT

Joseph R. Mango, Midlothian, Ill.

Application November 24, 1958, Serial No. 53,493

Term of patent 14 years

(Cl. D83—1)

Fig. 1

Fig. 2

Fig. 3

Fig. 4

Fig. 5

Figure 1 is a perspective view of a vibratory massage unit showing my new design;

Figure 2 is a rear elevational view;

Figure 3 is a top plan view;

Figure 4 is a front elevational view; and

Figure 5 is a side elevational view.

The dominant feature of my design resides in the portion shown in full lines. Fragmentary broken lines shown are for convenience of illustration.

I claim:

The ornamental design for a vibratory massage unit, as shown and described.
